UNITED STATES PATENT OFFICE.

WILLIAM T. BESSONETTE, OF TEMPLE, TEXAS.

DESIGN FOR A SPRAYER ATTACHMENT FOR WASHING-MACHINES.

SPECIFICATION forming part of Design No. 27,868, dated November 16, 1897.

Application filed September 27, 1897. Serial No. 653,259. Term of patent 3 $\frac{1}{2}$ years.

To all whom it may concern:

Be it known that I, WILLIAM T. BESSONETTE, a citizen of the United States, residing at Temple, in the county of Bell and State of 5 Texas, have invented a new and original Design for a Sprayer Attachment for Washing-Machines, of which the following is a specification.

This invention relates to a new and original design for a sprayer attachment for washing-machines, and it has for its object to provide a design of this character that shall be both useful and ornamental.

The leading feature of the design resides in 15 a conical base-plate having at its apex a short circular spout projection provided with perforations in its top, a circular group of upright inclined tubes arising from the base-plate near its periphery, and a circular band extending around the group of tubes and connected with the same at their upper ends.

A minor feature of the design resides in providing the conical base-plate with a pair of pendent circular concentric flanges, a central 25 circular opening within the plane of the inner flange, and a circular series of openings arranged between the two flanges. Another minor feature of the design resides in providing the inner pendent circular flange with a 30 peripheral series of openings and in providing the upright tubes at their inner upper ends with approximately semicircular openings.

In the drawings, Figure 1 is a perspective view of a sprayer attachment for washing-machines embodying the herein-described de-

sign. Fig. 2 is a vertical sectional view thereof. Fig. 3 is a bottom plan view.

Referring to the drawings, the numeral 1 designates a shallow conical base-plate provided with a peripheral pendent flange 2 and 40 an inner smaller pendent circular flange 3, concentric with the flange 2, and provided with a peripheral series of openings 4 therein. The said base-plate 1 is provided within the plane of the inner flange 3 with a central circular opening 5, and between the two flanges 2 and 3 with a circular series of openings 6. On its upper side and at the apex thereof the conical base-plate 1 is provided with a short circular spout projection 7, having perforations 7^a in its flat top, and a circular group of upright inclined tubes 8 arise from the base-plate near the periphery thereof and in line with the openings 6. The said upright inclined tubes 8 are provided at their inner 55 upper ends with approximately semicircular openings 9, and the entire group of said upright tubes is encircled by a circular band connected with the tubes at their upper ends.

What I claim is—

The design for a sprayer attachment for washing-machines, herein shown and described.

In testimony that I claim the foregoing as my own I have hereto affixed my signature in 65 the presence of two witnesses.

W. T. BESSONETTE.
